E. B. NICHOLS

TOY

Filed Sept. 27, 1921

Inventor,

Edgar T. Nichols.

Patented Apr. 1, 1924.

1,489,097

UNITED STATES PATENT OFFICE.

EDGAR B. NICHOLS, OF ROCHESTER, NEW YORK.

TOY.

Application filed September 27, 1921. Serial No. 503,695.

To all whom it may concern:

Be it known that I, EDGAR B. NICHOLS, a citizen of the United States of America, residing at Rochester, in the county of Monroe 5 and State of New York, have invented certain new and useful Improvements in Toys, of which the following is a full, clear, and exact specification.

This invention relates to toys, and particularly to a mechanism to be used as a toy for cutting out figures, etc., from sheet material. One object of my invention is to provide a device of this nature which will be simple to operate and cheap to manufacture; 10 another object is to provide a simple clamp for operating a punch; another object is to provide a platen which will bear against and transfer force to the punch without a sliding or scraping action; another object is to 15 provide a seat on the clamp into which a punch can be easily positioned and firmly held in operative position; another object is to provide a clamp which can readily be assembled; another object is to provide a 20 punch which cooperates with the clamp; and still another object is to provide a cooperating punch which is formed from a single sheet of metal. To these and other ends the invention consists in certain improvements 25 and combinations of parts as will be fully described in the annexed specification, the novel features being pointed out in the claims at the end of the specification.

In the drawing, in which like reference 30 characters denote like parts throughout:

Fig. 1 is a perspective of a toy constructed in accordance with and illustrating one embodiment of my invention;

Fig. 2 is a perspective view of the working 35 holding pad removed from the rest of the machine;

Fig. 3 is a side elevation of the main casting comprising the base and yoke;

Fig. 4 is an end elevation of the same casting, cooperating parts being indicated in dashed, and in dot and dash lines;

Fig. 5 is a perspective of the punch and die; and

Fig. 6 is a fragmentary side elevation of 50 one end of the lever, showing the clamping cam.

The clamp or press of my toy consists of a casting 1 having portions 2-2 and 3 to hold it erect upon a flat surface. A curved bracket 4 carries at its outer end 5 a lever 6,

which is pivoted by a pin 7 to the casting and which is operated by a handle 8, thus lowering the holding pad 9 through the cam surfaces 10-10 which contact with the inner side of the bottom face 11 of the pad. The 60 sides 12-12 of this member are slotted at 12'-12' so that it may move to and from the pin 7 which extends through the slots. The slideways 12'-12' permit of a swinging as well as a sliding movement so that face 11 65 always rests flat upon the member it engages. It should be noted here, by withdrawing pin 7 my device can be disassembled, this feature being important in facilitating packing for shipment, etc. The work in assembling 70 is likewise reduced to a minimum.

The casting 1 carries an anvil 13 upon which one end of the punch P rests when in operative position, there being a guideway 14-14 in the base of bracket 4 for supporting the other end of the punch. By moving the lever 6 in the direction shown by the arrow, Figure 1, it is obvious that the pad 9 is lowered toward the anvil 13, and that by continuing such movement considerable 75 pressure can be brought to bear on the moving part due to the design of the eccentric or cam portion 10 pressing on part 11. It should be noted that while the cam exerts a rotative or sliding force upon part 11, the 80 holding pad will convey only a downward pressure upon the member beneath it, as the bottom 11 of the pad is flat and it moves only in a vertical direction when in contact with a substantially flat surface. The sliding 85 action of the cam is entirely taken up by the pad surface 11 and is not transferred by it to the surface being clamped. This not only prevents marring and scratching, but materially assists in the smooth working of 90 my device.

The cutter, or the punch of my toy, consists of a male member 20 which cooperates with a female member 21, the latter being cut from one end of a strip 22 of metal and, 100 after being treated as described in my Patent No. 1,430,024, issued Sept. 26, 1922, is fastened to the other end of the metal strip to form the male member. The strip is bent at 23 to form a spring hinge, and, as is clearly 105 shown in the drawing, this fold does not bring the metal faces 24-25 adjacent the bend into contact, but provides for a sufficient separation at the bend to avoid cracking or otherwise weakening the bent portion, 110

and thereby impairing the spring of the metal. Outwardly flared lips 26 and 27 serve to guide the sheet material into the punch, and in addition provide a grip for the fingers of an operator, enabling him to open the jaws manually if they should by any chance stick together. But the spring hinge 23 normally holds the jaws in the position shown in Figure 6. A notch 28 is cut in the hinged edge of the punch forming a socket which interlocks with the bracket 4 by sliding into the guideway 14-14. This connection can be quickly and easily made by thrusting the punch between the anvil and pad and into a position where the notch 28 will engage the guideway 14-14, so that the punch will lie upon the anvil under the work pad. On the under side of the bracket 4 there is a stripping finger 30 which is positioned so that it passes a short distance through the female die each time this part is raised by spring 22. There is an aperture 31 in the work pad through which the finger 30 passes when the pad is raised into its upper position, thus removing the cut-out from the female die.

Where a variety of sizes and shapes of cut-outs are provided, as in the case of my present invention, it is possible that in some instances the female die (which I preferably mount on the upper jaw as shown) might present a large opening towards the upper clamping member, as is shown in Figure 5, where the position of the work pad 9 is illustrated by dashed lines. But with a work pad constructed as above described this is not material since the pad always engages sufficient portions of the female die (as at *a-a* Figure 5) to press the same down firmly. As the pad 11 is flat and there is merely a downward pressure without a sliding action, satisfactory results can be easily thus obtained.

The operation of my device is as follows: The desired cutter is selected and inserted into the clamp by first, raising the lever thereby separating the holding pad from the anvil, and second, thrusting the notch 28 into guideway 14-14, thus seating the male die upon the anvil 13. The female die 21 is held raised by spring 23, and the outwardly flared lips 26 and 27 serve as guides to direct a sheet of paper, for instance, into cutting position. The force of the spring 23 is also sufficient to hold the pad 9 in a raised position. By lowering lever 6, pad 9 is lowered by cam 10 pressing upon the inside of the flat bottom 11 thus causing the punch and die to function. By raising the lever the natural spring of the metal will separate the cutting parts and the paper, and will raise pad 9 so that the cutter can be easily removed. It should be noted that the upward movement of the female die causes the finger 30 to pass through the die, stripping the cut-

out therefrom. The cutter can now be removed if desired, and another substituted, as I contemplate supplying a number of different cutters with each outfit.

Having thus described my invention what I claim as new and desire to secure by Letters Patent is:

1. In a device of the class described, the combination with a clamp consisting of a base, a portion of the base for engaging a supporting surface, a bracket upon the base, a cam, a work-holding pad, and a lever for operating the cam, there being a pin by which the lever is pivoted to the bracket, said pin also supporting the holding pad. 80

2. In a device of the class described, the combination with a clamp, of a base on the clamp adapted to engage a supporting surface, a bracket extending up from said base, a pin passing through a portion of the bracket, a lever supported upon the pin, and a work-holding pad supported by the pin, and means including the lever for moving the pad with respect to the bracket. 85

3. In a device of the class described, the combination with a clamp, of a base adapted to engage a supporting surface, of a bracket extending up from the base, a pin passing through a portion of the bracket, a work-holding pad slotted to engage and slide about the pin, and means for moving the pad with respect to the bracket. 90

4. In a device of the class described, the combination with a clamp, of a base adapted to engage a supporting surface, of a bracket extending up from the base, a pin passing through a portion of the bracket, a work-holding pad slotted to engage and slide about the pin, a lever adapted to move the holding pad, and an anvil carried by the base, the clamping action being secured between the pad and the anvil, by the means operated by the lever. 100

5. In a device of the class described, the combination with a clamp and a guide-way 110 on the clamp, of a cutting device consisting of a punch and die adapted to be operated by the clamp, the punch and die having a slot in one end adapted to cooperate with the guideway of the clamp, whereby the cutting parts will be positioned for use. 115

6. In a device of the class described, the combination of a clamp, with a punch and die adapted to cooperate therewith, said punch and die consisting of a single piece of strip metal, folded upon itself to form jaws, and means in the strip metal for locating the punch and die with reference to the clamp. 120

7. In a device of the class described, the combination with a clamp, of a guideway on the clamp, a cutting device consisting of a male and a female die carried by jaws of sheet metal, the cutting device being 125 slidable to and from an operative position 130

with respect to the clamp, one end of the cutting device being engaged by the guideway on the clamp when the cutter is in an operative position.

- 5 8. In a device of the class described, the combination with cutter, of a clamp for operating the cutter comprising a base, a bracket extending up from the base, a lever pivoted to the bracket, a cam on the end of the lever, and a work pad supported by the bracket, said work pad being actuated by the cam to move in substantially a vertical path as the lever is rotated about its pivot, thereby causing the cutter to function.
- 10 9. In a device of the class described, the combination with a cutter, of a clamp for operating the cutter comprising a base, a bracket extending up from the base, a pin passing through the bracket, a lever supported by the pin, a cam on the end of the lever, a work pad supported by the pin, and an anvil on the base, the pad being moved toward the anvil by the cam as the lever is rotated upon the pin.

- 15 10. In a device of the class described, the combination with a base, of a bracket extending up from the base, a lever operably mounted on the bracket, an apertured work-holding pad operably mounted on the bracket, being adapted to move to and from the bracket, and a stripping finger carried by the bracket, the stripping finger being located in such a position that it will extend through the aperture in the work-holding pad when the pad is in one position.

- 20 11. In a device of the class described, the combination with a base, of a bracket extending up from the base, an anvil on the base forming a seat for a cutter, a cutter on the anvil, said cutter comprising hinged jaws movable to and from each other, one carrying a punch and the other the die, means for operating the punch and die, and means consisting of a stripping finger
- 25 45 for removing a cut-out from the die as the die moves away from the punch after the cutter has been actuated.

- 30 12. In a device of the class described, the combination of an operating clamp, with a cutter, said cutter consisting of a strip of metal bent upon itself to form spring jaws, one carrying a punch and the other a die, there being a notch in the cutter for placing the cutter in an operative position in the clamp.

- 35 13. In a device of the class described, the combination with an operating clamp hav-

ing a guideway, of a cutter adapted to slide into the guideway consisting of hinged strip metal jaws, one having a punch and the other a die.

40 14. In a device of the class described, the combination with a base, of a portion of the base adapted to engage a flat surface, a bracket affixed to the base and extending upwardly therefrom, a pin passing through the bracket, a lever and a work-holding pad carried by the pin, the former being adapted to turn about the pin and the latter to slide upon the pin, and means whereby the holding pad will be lowered from the bracket as the lever is turned upon the pin.

45 15. In a device of the class described, the combination with a base, of supporting members on the base, a bracket extending up from the base, and a pin extending through the bracket, a lever and a holding pad carried by the end of the bracket, being removable therefrom by removing the pin.

50 16. In a device of the class described, the combination of a base, with a bracket extending up from the base and over an anvil located upon the base, a work pad adapted to slide upon the bracket to and from the anvil, and means for forcibly moving the pad in one direction, the holding pad having a flat contacting portion, one side of which is adapted to press the work in one direction while the other side receives the impulse of the pad moving means.

55 17. In a device of the class described, the combination with a clamp consisting of a base, a bracket extending up from the base, of a work pad movably mounted upon the bracket, means for moving the pad in one direction, a cutter positioned on the base to be acted upon by the clamp, the cutter being adapted to move the pad in an opposite direction to the first mentioned moving means.

60 18. In a device of the class described, the combination with a clamp consisting of a base, a bracket upon the base, a work pad slidably supported upon the bracket, a cutter having spring jaws carried by the base, one of the spring jaws contacting with the work pad normally holding it in a raised position, and a means for moving the pad against the spring pressure of the jaws and thereby compressing the spring jaws together.

65 Signed at Rochester, New York this 23 day of September 1921.

EDGAR B. NICHOLS.
